BABY'S SHOE

Enrique Sanchez, New York, N.Y.

Application May 13, 1957, Serial No. 658,838

1 Claim. (Cl. 36—50)

This invention relates to the art of footwear and particularly concerns a novel infant's shoe construction.

Heretofore it has been found difficult to place a conventional laced type shoe upon the foot of an infant or young child because of the natural tendency of the infant or child to stiffen the arch of the foot and leg. Furthermore, the child tends to move his leg during lacing. The use of lacing on infants' shoes has also proven objectionable because of the tendency of the laces to loosen. Also securing and tying the laces require additional operations which are time-consuming and laborious. The provision of laces and eyelets or lacing holes in the shoe also increases the cost of the shoe.

The foregoing difficulties and disadvantages are overcome in the present invention by provision of a laceless shoe construction. The upper portion of the shoe at the back is provided with a slide fastener closure which permits the foot of the infant or child to be inserted into the shoe through the back thereof. A tongue member is provided at the back of the shoe to cover the slide fastener so that the infant cannot reach the slider of the slide fastener to open the closure. The shoe is made of a few simple standardized parts so that it is well adapted to mass production methods of manufacture and can be produced at low cost.

It is, therefore, a principal object of the invention to provide an infant's shoe with an opening at the rear closed by a slide fastener.

It is a further object to provide a laceless type of infant's shoe with a slide fastener covered at the interior and exterior of the shoe by a tongue which is secured at the exterior of the shoe by a snap fastener.

It is a further object to provide a child's shoe of the character described manufactured from simple standardized patterns.

Another object of the invention is to provide a laceless type of infant's shoe that is readily put on and taken off of an infant's foot.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a top plan view of an infant's shoe embodying the invention.

Fig. 2 is a vertical sectional view of a portion of the shoe taken on the plane of the line 2—2 of Fig. 1.

Fig. 3 is a side elevational view of the shoe.

Fig. 4 is a rear elevational view of the shoe.

Fig. 5 is a rear elevational view of the shoe with the tongue extended.

Fig. 6 is a top plan view of a portion of the shoe with the rear closure opened.

Fig. 7 is a rear elevational view of the shoe with the closure opened.

2

Figs. 8 through 13 are plan views of shoe pieces employed in manufacturing the shoe.

Fig. 14 is a view similar to Fig. 6 but showing modified means for attaching the tongue to the shoe upper.

Fig. 15 is an elevational view similar to Fig. 3 showing the free end of the tongue of Fig. 14 in fastened condition.

Referring particularly to Figs. 1 through 6 of the drawings, there is shown a shoe 18 having the upper portion

19 of its body formed from a single piece of sheet material 20, such as leather, plastic, composition sheet mate-

rial 20, or cloth. This sheet 20, as shown in Fig. 11, before assembly, is substantially rectangular in shape, with a semicircular cutout 21 at one side thereof. The ends

22 of the sheet 20 define the rear opening for the shoe.

15 A plug member 23 closes the cutout 21 and is secured by stitches or lacing 24 to the edge wall of the cutout. The shape of the plug member 23 is clearly shown in

Fig. 10. This is a flat piece with curved tapered sides

25 and with its narrow end 26 curved. Sheet 20 is se-

cured to the flat outer sole 27 along the peripheral edge

28 thereof. An upper heel counter section or cover 30 is provided at the heel of the shoe. This counter section

is best shown in Fig. 8, before assembly. It is generally

rectangular and has an upwardly extending tongue portion

31 in which is secured a centrally disposed female fas-

tening element 32. Counter section 30 is secured by stitch-

ing 33 to the sides of the upper portion 19 of the shoe.

At the rear of the shoe, in the interior thereof, an elon-

gated generally rectangular tongue 35, best shown in Fig.

30 12, is secured at one end to the base of the counter sec-

tion 30 at its center by stitching 34, as shown in Fig. 2.

The tongue is a rather wide member and its length is

about twice the height of the shoe. Except for its attach-

35 ment at its bottom end, its entire length is unattached

with respect to the upper portion 19. The curved edge

26 of plug member 23 and the upper edges 36, 36 of the

shoe upper 19 define the opening at the top of the shoe.

Tape members 37, 37 carrying interlocking elements 38,

38 of a slide fastener are secured to the edges 22 of the

opening in the upper portion 19 of the shoe at its rear by

stitching 39, and the opening is opened and closed by a

slide fastener member 40 slideable on the elements 38, 38.

The tongue 35 is provided at its other end with a male

45 snap fastener element 41 which is adapted to engage the

corresponding fastener element 32 on tongue 31.

When the rear of the shoe is closed as shown in Figs.

1—4 the slider 40 of the slide fastener is located near the

top of the shoe and tongue 35 extends upwardly at the

50 back of the shoe over the top thereof and down and

over the top end of the counter section 30. Snap fastener

elements 32 and 41 are engaged. In this position of the

parts the slider 40 is concealed by the tongue 35.

When the rear of the shoe is opened as shown in Figs.

55 5, 6 and 7, the slider 40 is drawn downwardly to its ex-

treme lowermost position. Edges 22 are widely separated

since the interlocking elements 38, 38 of the slide fasten-

er are disengaged completely. Tongue 35 is then bent

outwardly of the shoe, as best shown in Figs. 6 and 7.

This provides a wide opening at the rear of the shoe in-

tersecting with the top opening for insertion of the infant's

foot. After the foot of the infant is inserted into the shoe

55 with member 23 overlying the arch of the foot, the tongue

35 is drawn upwardly as shown in Fig. 5. The slider 40

is then drawn up to close the opening at the rear. The

60 tongue 35 is next bent over as shown in Fig. 4 so as to

snap the fastener elements 41 on to element 32 to com-

plete the closure of the shoe at the rear.

In Figs. 3 through 13 the simple construction of each

65 of the shoe parts of the shoe upper is clearly shown. Six

shoe parts are all that are necessary for assembly of the

shoe. This shoe construction is readily adapted to manu-

70 facture by mass production methods at low cost.

In Figs. 14 and 15, a modified means for securing the tongue 35' to the upper portion 19 of the shoe and for securing the free end of the tongue to the counter section or heel cover 30' of the shoe upper is shown. In this modification, the tongue 35' is secured along one of its long edges to the edge of one of the ends 22 of the shoe upper at the rear by a line of stitching 58, the remainder of the tongue being unattached. With this construction, the free end of the tongue is held in a convenient position out of the interference with the moving parts of the slide fastener.

The male snap fastening element 40' on the tongue 35' projects outwardly and the female fastening element 32' on the counter section or heel cover 30' opens inwardly so that when the tongue is turned over upon itself the fastener element 40' is projecting in a direction ready to be inserted into the fastener element 32', and when the fastener elements are in locking engagement, the free end of the tongue 35' is on the inside, of the counter section 30' that is, inwardly, of the heel cover 32' so that it is difficult for an infant to get hold of it for pulling in an effort to open the shoe.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

An infant's shoe comprising a sole, an upper portion

on the sole having an opening at the rear extending from the top to the bottom thereof, tapes secured along the edges of said opening, slide fastening elements fastened on the adjacent edges of said tapes, a slider member slidably on said elements for actuating said elements into open and closed positions, a cover secured to the upper portion at the rear thereof adjacent the sole, said cover having an unattached portion extending over the bottom end of said tapes, a female snap fastener element on said unattached portion opening inwardly, an elongated rectangular shaped flexible tongue member disposed inside said tapes for covering said slide fastening elements and being secured along one long edge to the inner surface of one end of the upper portion adjacent the respective tape, the remainder of said tongue member being unattached, said tongue member being twice as long as the height of the upper portion of the shoe, said tongue member extending downwardly to the sole, inside the cover, and a male snap fastener element on the free end of said tongue member positioned so that when said tongue member is turned upon itself, said male fastener element projects in a direction adapted to engage said female fastener element, the free end of said tongue member when said snap fastener elements are in engagement being inside the cover.
